CLAIM

The ornamental design for a pencil with cap and stylus, as shown and described.

DESCRIPTION

FIG. 1 is a perspective view of the pencil with cap and stylus of the present invention;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The broken lines shown in the drawings are included to show portions of the pencil with cap and stylus that form no part of the claimed design.
